UNITED STATES PATENT OFFICE.

ALBERT H. KYLER, OF WESTMINSTER, MARYLAND.

BOXING OR CASING MACHINE.

Application filed July 7, 1927. Serial No. 204,115.

This invention relates to improvements in machines for boxing and casing cans and more particularly to power-driven mechanism for operating such machines,—one object of the invention being to provide simple and efficient mechanism operated by a motor for actuating the pusher member of a can boxing machine and to provide simple and efficient means whereby the operation of said mechanism may be readily controlled by an attendant.

With this and other objects in view, the invention consists in certain novel features of construction and combinations of parts as hereinafter set forth and pointed out in the claims.

In the accompanying drawings:

Figure 1 is a view in side elevation showing an application of my improvements to a can boxing machine;

Figure 2 is a plan view of a portion of the machine and

Figures 3 and 4 are views showing details.

My improvements are shown in the drawing as applied to a boxing machine of the general type disclosed in patent granted to me on the 2nd day of September 1924 and designated by No. 1,507,387. The machine comprises a framework 1; an assembling frame 2 for cans and to which the cans are fed by suitable means so that they will be disposed in layers; a pusher 3 to enter the assembling frame and engage cans therein to move the layers of cans forwardly, and a lever frame 4 pivotally connected with the framework and connected with the pusher for operating the same. The lever frame 4 may be provided with arms 5 depending from the same at its pivotal mounting. Springs 6 may be attached at one end to the framework and their other ends to said depending arms so that they will operate to retain the pusher normally in and return the same to its retracted or withdrawn position.

Mounted in suitable bearings 7, 7 on the framework, preferably over the assembling frame 2 is a shaft 8, and pivotally mounted between upper portions of the uprights of the lever frame 4, is a bar 9. The body of this bar may be angular and it is provided in its center with a transverse hole for the free passage of a rod 10, with one end of which, one end of a flexible device 11 is connected, the other end of the device 11 being connected with the shaft 8. The rod 10 is threaded to receive a nut 12, between which

and the bar 9, a spring 13 is located so that the device shall have a yielding connection with said bar 9. In the embodiment of the invention shown in the drawing, the flexible device 11 is a strap or belt and it is connected with the shaft 8 preferably by means of a hinge structure 14. I do not, however, restrict myself to the use of a belt or strap, as the flexible device 11 may consist of a chain or cable to wind on the shaft 8. It is apparent that if the shaft 8 be rotated in one direction, the flexible device will be wound thereon and the pusher will be pulled forwardly and made to enter the assembling frame and move the cans forwardly so as to be deposited into a box or case. The forward movement of the pusher will be against the resistance of the springs 6 so that when driving power is removed from the shaft 8, said springs will serve to cause the pusher to be retracted. The shaft 8 is driven by a motor 15 (preferably an electric motor) which may be conveniently mounted upon the framework in proximity to the assembling frame. The shaft 8 is extended at one end beyond one of its bearings and has secured thereto, a clutch disk 16 and with the latter, a clutch disk 17 loose on said shaft is cooperable. The loose clutch disk 17 is carried by a loose sleeve 18 and these parts carry a sprocket wheel 19. The clutch disk 17, sleeve 18 and sprocket wheel 19 may, if desired, be made in one integral structure loosely mounted on the shaft 8. A sprocket chain 20, transmits power from a suitable wheel on the shaft of the motor to the sprocket wheel 19 for imparting power to the shaft 8 when the clutch disks are in operative engagement with each other.

Arms 21, 22 project laterally from the framework and provide bearings for a shaft 23 having an arm 24 and this arm may be provided with a ball-member 26 to engage the closed end of the sleeve 18. A spring 27 coiled on the shaft 23 and connected therewith and with the arm 22, tends to turn said shaft in a direction to relieve the pressure of the arm 24 against the closed end of the sleeve 18. An arm 28 is secured to the shaft 23 and is connected, through the medium of an adjustable connection 29, with a foot lever 30 suitably mounted in the lower portion of the framework. It is evident that by pressing the foot lever, the arm 28 will be depressed in a manner to turn the shaft 23 and cause pressure of the arm 24 against the sleeve 18 to shift the clutch disk 17 into

operative engagement with the clutch 16 and thus cause rotation of the shaft 8 by power derived from the motor. Slight pressure only of the clutch disk 17 against the clutch 5 disk 16 will suffice to cause sufficient power to be imparted to the shaft to operate the lever frame and pusher against the resistance of the springs 6 and the degree of pressure of the disk 17 against the disk 16 when 10 the foot lever is depressed, may be regulated by a set screw 31 carried by the arm 28 and cooperable with the framework.

The movements of lever frame for operating the pusher is limited in one direction 15 by one or more set screws 32 carried by the framework and in the other direction by a cross bar 33. The strap 11 may be of such length that the yielding connection of the same with the lever frame will operate to 20 cushion the latter at both ends of its throw.

It may be stated that the machine is somewhat inclined (as clearly illustrated in my former patent hereinbefore identified) and the shaft 8 will therefore be somewhat inclined. A very slight movement of the clutch member 17 will suffice to remove driving power from the shaft 8, and the inclination of this shaft will suffice to cause the disk 17 to tend to move away from the disk 16, when the 30 operator releases the foot lever. Should the operator fail to release the foot lever at the proper time, the clutch members would slip, but in order to protect the motor from possibility of injury by overload in the event 35 the foot lever be not released at the proper time, the devices now to be described may be employed. A slide 34 is mounted upon the framework and formed at one end to provide a wedge 35 to project under the head at 40 the lower end of the screw 31 and the slide is moved in a direction away from said head by a spring 36. The slide is provided with a lateral arm 37 carrying an adjustable screw 38 in the path of movement of a portion of 45 the lever frame 4. With such construction, it is apparent that when the lever frame and pusher shall have moved to the extent of their forward movement, a portion of the lever frame 4 will engage the screw 38 and 50 cause the slide to move sufficiently to project the wedge under the head of screw 31 and raise the arm 28, thereby causing the shaft 23 to turn and permit release of the clutch. Thus it will be seen that the clutch is 55 released automatically when the lever reaches the end of its forward throw and that the motor will be protected against overload.

It is evident that with my improvements, 60 pressure on the foot lever will cause the lever frame and pusher to be pulled forwardly by power derived from the motor and that when the foot lever is released, power of the motor will be removed from the pulling shaft 8 and the lever frame and pusher will be retracted by the action of the springs 6.

Various changes might be made in the details of construction of my invention without departing from the spirit thereof or limiting its scope and hence I do not restrict myself to the precise details herein set forth. 70

Having fully described my invention what I claim as new and desire to secure by Letters-Patent, is:—

1. The combination in a boxing machine including a pusher, of a shaft, means for connecting said shaft with said pusher, a motor, operative connections between said motor and the shaft including clutch devices on the shaft, said shaft being inclined whereby clutch devices are normally disengaged, a shaft at an angle to the first-mentioned shaft having an arm arranged to effect engagement of the clutch devices, a spring tending to turn said last-mentioned shaft in the direction to release the clutch devices, and an operator-controlled means for setting said last-mentioned shaft to engage the clutch devices. 80

2. The combination in a boxing machine including a pusher, of a shaft, means for connecting said shaft with said pusher, a motor, operative connections between said motor and the shaft including clutch devices and a rocking arm controlling the clutch devices, operator-controlled means for rocking said arm to close the clutch devices, and means for adjusting the throw of said arm. 90

3. The combination in a boxing machine including a pusher, of a shaft, means for connecting the pusher and the shaft, a motor, operative connections between said motor and the shaft including clutch devices, a rock shaft having an arm for effecting engagement of the clutch devices, a second arm carried by said rock shaft, a foot lever, connecting means between said last-mentioned arm 100 and said foot lever, and yieldable means acting on the rock shaft in opposition to the foot lever. 105

4. The combination in a boxing machine including a pusher, of a shaft, means to connect the pusher to said shaft, a motor, operative connections between said motor and the shaft including clutch devices, a rock shaft having an arm for effecting engagement of the clutch devices, a second arm carried by 115 said rock shaft, a foot lever, connecting means between said last-mentioned arm and said foot lever, means to adjust and limit the throw of said last-mentioned arm, and yieldable means acting on the rock shaft in opposition to the foot lever. 120

5. The combination in a boxing machine including a pusher, of a motor, operator-controlled connections between the motor and said pusher whereby to move the pusher forward, said connections including clutch devices, and means including a member projecting into the path of the pusher adjacent the forward limit of its movement and operable automatically by the forward throw of the 125 130

pusher to release the clutch devices, said member being free of the pusher and the operator-controlled connections and actuated by impact from the pusher.

- 5 6. The combination in a boxing machine including a pusher and a lever connected therewith, of a motor, connections between the motor and said lever, said connections including clutch devices, operating means for
- 10 10 the clutch devices, said operating devices including an arm, and a spring-retained sliding wedge for moving said arm to release the clutch devices, said wedge having a part in the path of forward movement of said lever.
- 15 15 7. The combination in a boxing machine

including a pusher and a lever connected therewith, of a motor, connections between the motor and said lever, said connections including clutch devices, operating means for the clutch devices, said operating devices including an arm, a set screw carried by said arm, a slide having a wedge end cooperable with said set screw, a spring for retaining said slide in and returning it to normal position, and an adjustable screw carried by said slide and disposed in the path of forward movement of said lever.

In testimony whereof, I have signed this specification.

ALBERT H. KYLER.
